United States Patent Office.

GEORGE NEWCOMER, OF CLEVELAND, OHIO.

Letters Patent No. 101,906, dated April 12, 1870.

IMPROVED STOVE-PIPE SHELF.

The Schedule referred to in these Letters Patent and making part of the same.

Be it known that I, GEORGE NEWCOMER, of Cleveland, in the county of Cuyahoga and State of Ohio, have invented a certain new and improved Stove-Pipe Shelf, of which the following is a specification.

Drawings.

Figure 1 is a side view of the shelf.

Figure 2, a view of the top.

Like letters of reference refer to like parts in the different views.

Specification.

This invention relates to a shelf, the same being attached to a stove-pipe, from and around which it projects.

It is also provided with a series of holes, into which bowl cups are placed for being kept warmed.

Said shelf is also provided with adjustable extension bows and arms.

It further relates to the manner of securing said shelf to the pipe, so that it can be attached thereto or removed therefrom without taking down the pipe, as hereinafter more fully set forth.

General Description.

In fig. 1—

A represents a section of stove-pipe, to which the shelf is attached.

Said shelf is constructed in two sections, B C, fig. 2, which are connected to each other as follows:

Section C is provided with a lug, D, in which is a hole, E.

In that part of section B corresponding to lug D is secured a catch, which is made to catch into the hole or eye E, and thereby hold the two sections firmly together.

G, fig. 2, are two slots, running lengthwise the diametrical division of the two sections.

It will be observed that the sections of the shelf between the slots and edge thereof are tapering toward the center, forming wedge-shaped keys, H H, whereby the two sections of shelf are secured to each other by clamps, I, which, as will be seen, embrace the two wedge-shaped keys.

It will be obvious that by this clamp the two sections of shelf can be very firmly secured to the pipe. Thus two sections of shelf are placed one on each side of the pipe. The hook is then inserted in the eye, whereby that side of the shelf is held.

On bringing the two opposite sides together, the clamp is slipped onto the keys and then forced toward the periphery of the shelf.

In consequence of their wedging-shape, the two sec-

tions are drawn together, thereby embracing the pipe, more or less tightly, as the clamp may be forced upon the keys.

By this simple device the shelf can be easily and readily attached to the pipe or removed therefrom, or adjusted in its height from the stove, as may be required.

It will be seen that the ends of the clamp are not joined to each other, but that there is a space, a, fig. 1, between its extreme ends, the purpose of which is to allow of the clamp being taken off or put on the clamping-keys.

To give greater security to the shelf in its attachment to the pipe, a deep band or collar, J, fig. 1, is secured to the under edge of the hole in the shelf, and immediately in contact with the pipe, so that, if one side of the shelf should be loaded more than the other, the collar will act as a brace, thereby preventing said loaded side from sagging in consequence of the weight thereon.

The several holes J in the shelf are for receiving the vessels placed thereon, so that they cannot fall off in consequence of being pushed against or from any jarring or shaking of the stove.

The double hole, K, is for holding a lamp, the globe of which is passed through the larger hole, and the neck thereof slipped along into the smaller one, and in which it hangs with perfect safety.

L L' are rods and exterior bows, the inner ends of which are inserted in some one of the several holes, and then under the inner edge thereof, which are thereby held in a horizontal position, as shown in the drawing.

Said rods and bows are prevented from displacement by grooves, b, into which they are received. On said rods may be hung articles for drying, &c.

The purpose of the bows L' is for the extension of the shelf, which, as they project from beyond the edge thereof, obtain for the shelf an increase of holding-capacity, so that utensils of large size can be supported upon the shelf by partially resting upon the extending bows.

The same object is obtained, though in less degree, by the ears P, projecting from the sides of the shelf, the general outline of which is circular and of a certain width, so that the ears, in projecting therefrom offer a rest for larger-sized utensils than could be securely held upon the shelf, if used without them.

I am aware that shelves attached to stove-pipes have been used, but these I do not claim. I am also aware that rods have been used in connection with such shelves, on which to hang clothes, but rods *per se* I do not claim; but

That which I do claim as my invention, and desire to secure by Letters Patent, is—

1. A shelf, when constructed in two sections, B C, and connected to each other by a hook and eye, E F, or its equivalent, wedging-keys H H, and clamp I, substantially as described and for the purpose set forth.

2. The combination of the shelf with the rods L and bows L', when constructed and arranged in relation to each other substantially as and for the purpose specified.
